COIN CONTROLLED LIQUID DISPENSING APPARATUS

Weir S. Bates, Mechanicsburg, Pa.

Application January 12, 1931, Serial No. 508,215

8 Claims. (Cl. 194—13)

This invention relates to coin-controlled liquid dispensing apparatus, and more particularly to means whereby a type of motor-driven dispensing apparatus now commonly employed at gasoline filling stations, under the direction of attendants, may be operated automatically by the insertion of coins to deliver quantities of gasoline proportioned to the value of the coin, and whereby the quantity of gasoline delivered may be varied according to the current market price of the gasoline.

In the type of apparatus to which my invention relates, as usually operated, an attendant starts a motor which operates the pump, opens the valve leading to the hose, and when the end of the nozzle on the hose is inserted in the supply tank of a motor vehicle, a valve in the nozzle is opened by the attendant and the liquid then flows from the pump through a metering device and thence through the hose to the tank.

In carrying out my invention I provide means whereby, upon inserting a coin in a coin chute and moving a coin-connecting bar, the motor which operates the pump will be automatically started and the valve leading to the hose will be automatically opened. Then, upon opening the valve in the nozzle, the flow of liquid through the metering device causes the latter to actuate a tripping mechanism which operates, after a predetermined quantity of gasoline has been delivered, to close the valve at the inner end of the hose, to open a switch which stops the motor and pump and to restore the various parts of the mechanism to their normal positions. The invention includes means whereby the quantity of gasoline delivered will be in proportion to the value of the coin inserted in the machine and also the quantity delivered may be varied to correspond with changes in the market price of gasoline.

In the accompanying drawings:

Fig. 1 is a vertical section through the apparatus, approximately on the line 1—1 of Fig. 2, the enclosing casing being shown partly in side elevation and partly in section;

Fig. 2 is a view showing the mechanism in elevation, looking from right to left in Fig. 1, the casing being shown partly in section;

Fig. 3 is a top plan view of the coin-operated mechanism, and showing also the rods which move the switch lever;

Fig. 4 is a front view of the coin-operated mechanism, the clutch and connecting link being omitted;

Fig. 5 is a rear elevation of the same;
Fig. 6 is a top plan view of the coin-connecting bar;

Fig. 7 is a perspective view of the lever for restoring the coin-controlled levers to their normal positions;

Fig. 8 is a detailed view of the mechanism shown in the central part of Fig. 2, the meter and parts above the meter shaft being omitted;

Fig. 9 is a detailed view of the tripping bar 10 and associated parts;

Fig. 10 is a vertical section through the same;

Fig. 11 is a view showing in detail the mechanism illustrated in the lower part of Fig. 1, for operating the rod which opens the outlet 15 valve and for actuating the resetting lever, the various parts being shown in their normal positions;

Fig. 12 is a view similar to that shown in Fig. 11, partly broken away, showing the positions of the parts while the drive-shaft is in operation;

Fig. 13 is an enlarged side elevation of the tripping mechanism, the parts being in normal position;

Fig. 14 is a similar view illustrating the action of the tripping mechanism when a coin of the smaller denomination is used to operate the machine;

Fig. 15 is an enlarged side elevation of the tripping mechanism showing the wedge locked in its lower position, as at the commencement of operation by a coin of the larger denomination, the cams being omitted;

Fig. 16 is a similar view illustrating the tripping operation, and

Fig. 17 is a section on the line 17—17 of Fig. 15.

Referring to Figs. 1 and 2 of the drawings, *a* represents an upright casing in which the apparatus is enclosed. In one side of the casing 40 are coin slots from which coin chutes *1* and *2* lead downwardly to coin controlled mechanism for closing a switch *b* to start an electric motor *c*. The chute *1* is adapted to receive coins of one size and denomination, as for instance 25-cent pieces, and the chute *2* is adapted to receive coins of larger size and denomination, as for instance 50-cent pieces. The coin operating mechanism is, in its essential features, the same as in my Patent No. 1,183,522, dated May 16, 1916. A coin dropped into the chute *1* enters a slot *1a* (Fig. 3) formed by a cross piece *3a* on a yoke *3* and a stationary bar *4*, and rests on roller *5* supported by bar *5a*. Similarly, a coin dropped into the chute *2*, enters a slot *2a* 55

between a cross piece 6a on a yoke 6 and the stationary bar 4 and rests on a roller 7. The yoke 3 has one arm 3b pivoted in the bar 4 and a parallel bar 8, and the opposite arm 3c extends through arcuate slots 9 in said bars. The arm 3c also carries a roller 10 which lies in the plane of the roller 5. Similarly, the arm 6b of the yoke 6 is pivoted in parallel bars and the arm 6c is movable in slots 10 in the bars and carries a roller 11. A triangular bell crank lever 12 is secured to the ends of the yoke 3 and a similar lever 13 is secured to the ends of the yoke 6.

A notched connecting bar 14 is movable horizontally beneath the coin slots 1a and 2a by means of a crank shaft 15, upon which is a one-way clutch 16 connected by a link 17 to the connecting bar, whereby one revolution of the crank shaft will cause the connecting bar to move to the left in Figs. 3 and 5, or to the right in Fig. 4, and then return to the position shown in said figures. If a coin is dropped into the slot 1a and the crank shaft is turned, the coin will be carried by the connecting bar under the roller 10 and will rock the arm 3c of the yoke upwardly and swing the lower end of the lever 12 to the left in Fig. 5, and after passing under the roller the coin will drop into a pocket 18 (Fig. 1) and the connecting bar will then return to its original position. Similarly, a coin dropped into the slot 2a will rock the yoke 6 and the lever 13 when the crank is given a complete turn.

The lower end of the lever 12 is pivotally connected by a link 19 to a swinging arm 20, which is pivoted at 20a to the bar 8 and depends therefrom, so that any rocking movement of the lever 12 causes a corresponding rocking movement of said arm. A yoke 21 on one side of the link 19 is engaged by one arm d' of a restoring lever d, and one arm 21a of this yoke forms a convenient pivot pin for connecting the link with the lever 12. A link 22 is pivoted at one end to the lower end of the lever 13, and this link has a slot 22a through which the arm 21a of the yoke 21 extends. It will be seen from this construction that if the lever 12 is swung to the left in Fig. 5, the supporting arm 20 will swing with it, without moving the lever 13; but if the lever 13 is swung to the left in said figure, it will, through the links 22 and 19, swing the supporting lever 20 to the left and also the lever 12. A rod 23 is pivoted at one end to the supporting lever 20, and its opposite end has a slot 23a into which the lever 24 of the switch b extends. When the lever 20 swings to the left as in Fig. 8, this rod is moved to close the switch and start the motor; but when the rod is returned to its normal position, it does not operate the switch lever, owing to the lost motion connection between the rod and the switch lever.

The restoring lever d, as shown in Figs. 3, 4, 5, 7 and 8, is a forked lever having its lower end pivoted to a supporting bracket 24, and having a short arm d' which extends into the yoke 21, and a longer arm d² which projects upwardly at the rear end of the coin connecting bar 14. When a coin is inserted in the machine and the crank is turned, the connecting bar moves the coin to rock one of the levers 12 or 13, and the switch is thrown to the "on" position. During this movement the yoke 21 causes the restoring lever d to move and its arm d² follows the connecting bar 14 to the limit of its forward movement, as shown in Fig. 8. When the bar starts on its return movement, it bears against the arm

d² and rocks the restoring lever backward, and its arm d', engaging the yoke 21, moves the link 19 to the position shown in Figs. 4 and 5, thereby returning the supporting arm 20, switch rod 23 and lever 12 to normal positions, and also the lever 13, if the latter has been moved from normal position.

From the foregoing it will be seen that by inserting a coin in either coin slot and turning the crank arm, the motor will be started and then the coin controlled mechanisms will be returned to normal positions without opening the switch. The function of the lever 12, when operated by a 25-cent coin, is merely to close the switch, while the lever 13, when operated by a 50-cent coin, causes the switch to close and also causes adjustments to be made whereby the amount of gasoline delivered will be in proportion to the value of the coin used.

In the type of gasoline dispensing apparatus to which my invention relates, the liquid is forced by a pump, operated by the motor c, through a metering device g and thence to an outlet fitting 25 to which is attached a hose 26, and the hose is provided with a nozzle 27 having a normally closed valve 28 which may be opened by the operator after the nozzle has been inserted in the filling opening of an automobile tank.

The fitting 25 is provided with a valve 29 which is held normally closed by a spring 30 connected to the valve lever 30a, as shown in Fig. 2. The metering device operates a hand 31 which turns about a dial 31a having a scale which indicates the amount of liquid passing through the meter. In the present invention the hand is mounted upon a shaft 32 which is operated by the metering device.

A drive shaft 33 is mounted in the lower part of the casing and suitably geared to the motor, as by a sprocket wheel 34 and chain 35. Upon the drive shaft is a friction clutch 36 composed of disks which rotate with the shaft and a driven member 38, consisting of a flat crank arm which is loosely journaled on the shaft and frictionally gripped by the disks under the pressure of a spring 37. The crank arm, as shown in Figs. 11, 12 and 16, is connected by a link 39 to the lower end of an upwardly extending lever 40 which is pivoted at 40a to the frame of the machine. The upper end of the lever 40 is connected by a link 41 to an arm 42 which is pivotally mounted on the shaft 32 and adapted to reset certain of the devices in their initial positions, as hereinafter explained. The link 39 is centrally pivoted to the driven clutch member 38 at 38a and the rearward part 39a of the link has an overturned end 39b adapted to engage the member 38 and limit the movement of the latter when the shaft 33 is turned by the motor in the direction of the arrow, Fig. 12.

An L-shaped bracket 42b, secured to the frame, has on its foot 42a a guide pin 43 which extends through a perforation in the foot 44a of an L-shaped member 44, one end of which is pivotally connected to the lever 40 at 45. A helical spring 46 surrounds the pin 43 and is interposed between the foot 44a and an adjusting nut 43a on the pin. The spring normally holds the foot of the member 44 against the foot of the stationary member 42b, and the lever 40, restoring arm 42 and clutch member 38 normally occupy the positions shown in Fig. 11. When the motor starts, the frictionally driven crank 38 is carried to the position shown in Figs. 12 and 16 and is stopped by the engagement of the shoulder 38b

on the link 39 with the edge of the member 38, as shown in said latter figures, while the shaft and the friction disks thereon continue to turn. As the clutch member 38 moves to the position shown in Fig. 12, the lever 40 and the arm 42 move to the positions shown in said figure and the lever 40 moves the L-shaped rod 44 and compresses the spring 46. When the current is cut off from the motor and the drive shaft 33 slows down, the spring 46, through the connections described, causes the clutch member 38 to slip backward and reset the parts in the positions shown in Fig. 11.

When the motor starts and the clutch member 38 is turned from its normal position to the position shown in Figs. 12 and 16, a rod 47 is pulled downwardly against the action of the spring 30 (Fig. 2) and this downward movement of the rod opens the valve 29 to permit gasoline to enter the hose. The rod 47 is connected to the clutch member 38 through a mechanism which releases the rod and allows it to move upwardly to close the valve as soon as the switch b is operated to stop the motor c. As shown, a link 50 is pivoted at one end to a bracket 51 and has a pin 52 projecting laterally from its opposite end. A link 53 connects this pin with the frictionally driven member 38, and the pin projects through a longitudinal slot 54 in the rod 47. A latch 55, pivoted at 56 to the lower end of the rod 47, is normally held under the pin 52, as shown in Fig. 11, by a spring 57 which surrounds a pin 58 on the upper end of the latch and is interposed between the head of the pin and a flange 59 on the rod 47.

As the latch normally extends under the pin 52, the link 53 will draw the rod 47 downward and open the valve 29 each time the drive shaft 33 is started by the motor, and the rod will stay down until the pin 52 is released by the latch, when the spring 30 will draw the rod up and close the gasoline outlet valve. For releasing the latch a lever 60 is provided, and this lever is pivoted to an arm 61 on the rod 47, and is also pivotally connected at 62 to the upper end of the latch. The lever has at its free end a flange 60a which is perforated, and a tappet rod 63 extends through this flange and has an adjustable tappet member 64 threaded onto its end. The tappet rod extends upwardly and is connected to one end 65a of a lever 65 which is centrally pivoted upon a bracket 66. The opposite end of said lever is connected by a link 67 to the lower end of a rod 68 which extends upwardly for some distance above the shaft 32 and is pivotally connected at its upper end to the upper end of bar 69 which is journaled near its lower end on the shaft 32. The rod 68 is bent so that its point of pivotal connection, 68a, with the bar 69, will be normally at the right of a line passing through the axis of the shaft and the lower pivotal point 68b of the rod, as shown in Figs. 13 and 15; but when the bar 69 is moved to the left, as indicated in Fig. 16, until the pivotal point 68a passes beyond said line, a coiled spring 70, having an arm which bears downwardly upon a pin 68b at the lower end of the rod 68, draws said rod quickly downward, and the centrally pivoted lever 65 is rocked as shown in Fig. 16, raising the tappet rod 63, and the tappet 64 thereon operates the lever 60 to move the latch 55 and thereby unlock the pin 52 from the rod 47, and the spring 30 thereupon moves the latter rod upwardly to permit the outlet valve 29 to close.

This downward movement of the rod 68 also

operates to open the switch b and thereby cut off current from the motor c which operates the drive shaft 33 and the pump. As shown in Figs. 2, 3 and 8, a lever 72 is secured to a shaft 73 and this shaft has a crank arm 73a connected to a flange on the link 67. To the free end of the lever 72 is connected a rod 74 having a hook at one end for moving the switch lever 24 to the "off" position. Thus the valve 29 is closed immediately when the bar 69 swings past a certain point and the current is then immediately cut off from the motor.

When the electric motor is started by the insertion of a coin of the smaller denomination in the chute 1 and turning the hand crank, the pump, in the type of dispensing apparatus to which my invention is applied, starts into operation, and the valve in the outlet 25 is opened, but no gasoline flows through the metering device and hose until the operator opens the valve in 20 the nozzle at the free end of the hose. When this happens, the metering device turns the shaft 32 in the clockwise direction, looking from left to right in Fig. 2, to carry the pointer 31 around on the dial 31a to indicate the volume of gasoline 25 delivered through the hose. When the electric motor starts, the restoring arm 42 is also moved from the position shown in Figs. 1, 11 and 13 to the position shown in Figs. 12 and 14 by the operation of the motor, as heretofore explained. 30

When the metering device operates the shaft 32, the latter carries with it two cam members e and f, which are secured together and to a sleeve 75 (Fig. 8) which is slidable to a limited extent longitudinally of the shaft, but held against 35 rotation thereon by a collar 76 having a tongue 76a which extends into a longitudinal slot in the sleeve. A helical spring 77 interposed between the collar and the cam members urges the latter toward a rod 78 which is vertically movable between the cam members and a stationary part 79 through which the shaft extends. The upper end 78a of this rod is bent into the form of a loop to form a wedge, so that when the rod is pulled downwardly, it will force the two cam members 45 to the left in Figs. 2 and 8 against the pressure of the spring, and when the rod is moved upwardly, the spring will press the cam members closer to the part 79. The looped end of the rod is vertically slotted as shown at 78b, Fig. 10, 50 and the shaft extends through this slot.

The cam members e and f are made of sheet metal, riveted together in their lower portions and having their upper portions spaced apart and lying in parallel planes. The member e has 55 a cam surface 80 and the member f has a cam surface 81. The tripping arm 69 has a longitudinal guide slot 69a, and a plate 82 is longitudinally adjustable on the arm by means of screws 83 and 84 which extend through the slot and into the 60 plate. This plate has a lateral extension 82a, the end 82b of which is turned over to form a shoulder adapted to be engaged by the cam surfaces of the members e and f. A vernier plate 85 is loosely mounted on the shaft 32 and has a 65 slot 86 through which the screw 84 extends. This slot is at right angles to the slot 69a when the plate 82 is in its lowermost position. By loosening the screws 83 and 84 and adjusting the vernier to the left, in Fig. 9, the plate 82 will be 70 moved upwardly and its shoulder 82b will be raised with respect to the cam surfaces of the cam members e and f. An arcuate scale 87 on the vernier plate is readable along the edge 82c of the plate 82. This adjustment, as will be here-

inafter more fully explained, is to vary the amount of gasoline delivered according to the price at which gasoline may be selling. After the plate 82 has been adjusted to any desired position, the screws 83 and 84 will be tightened to hold said plate and the vernier in their adjusted positions.

The shoulder 82b on the plate 82 projects across the planes of the upper parts of both of the cam members e and f, when the wedge member 78 is in its upper position, and if these members be rocked to the left, by the rotation of the shaft 32, from the position shown in Fig. 13 to the position shown in Fig. 14, the cam surface 81 on the member f will engage said shoulder and continued movement of the cam member will cause the tripping arm 69 to pass over the center of the shaft and thereby allow the rod 68 to drop, as shown in Fig. 16, and operate the switch b to its "off" position and also release the latch 55 to permit the rod 47 to move upwardly and close the outlet valve 29. The time at which this tripping action will occur depends upon the adjustment of the plate 82 on the tripping arm. If it is adjusted radially outward on the arm, the cam surface 81 will engage the shoulder later in the operation of the shaft 32, which is operated by the metering device, and hence more gasoline will be delivered before the parts are tripped.

If the wedge member 78 is pulled downward, it moves the cam members e and f away from the plate 82 so that the member f will pass by the shoulder 82b and said shoulder will be engaged at a later period in the operation of the meter shaft by the cam surface 80 on the member e, which is back of the cam surface on the member f. Hence a greater quantity of gasoline will pass through the meter before the member e engages said shoulder and trips the member 69 to open the switch which controls the electric motor and to close the valve 29.

When a 25-cent coin is used to operate the motor, the wedge member 78 remains in its upper position and the cam member f trips the parts which close the outlet valve 29 and cut off the current to the motor when a given amount of gasoline has been delivered; but when a 50-cent coin is used, the wedge is pulled down automatically and locked in its lowered position, thereby adjusting the cam members so that the member e will trip said parts after a proportionately greater amount of gasoline has been delivered.

The wedge-piece 78, as shown in Figs. 13 to 16, extends below the shaft 32 and is pivotally connected at its lower end to the free end of the lever 90 by a pin 91. The opposite end of said lever is pivoted to a stationary bracket 92. A wire link 93 is pivotally connected at one end to the lever 90, and the opposite end of the link is formed into a relatively long loop which extends through a relatively long slot 94a in an arm 94b of a lever 94 (Fig. 8). This lever is connected by a link 95 to the lower end of the coin controlled lever 13 which is operable by 50-cent coins.

When the lever 13 is rocked by a coin, through the connections just described, the wedge member 78 is pulled downward to the position shown in Figs. 8 and 15, thus setting the cam members e and f in the position where the member f will be out of line with the shoulder 82b and only the cam member e can engage said shoulder. The wedge member is automatically locked in this lowered position, as shown in Fig. 15, by the following mechanism: A locking plate 96 is pivot-

ally suspended from a fixed support 79, by a stud or screw 98, and hangs downwardly from the support. This plate has an L-shaped slot 99, one part of which extends longitudinally of the plate and the lower part of which extends transversely of the plate. The pin 91, which connects the lever 90 with the wedge strip 78, extends through said slot. A stirrup 100, pivoted on the stud 98, lies against the plate 96 and has a flange 101 at its lower end. A rod 102 pivoted at its lower end on the pin 91 extends upward through a hole in said flange and has a head 102a at its upper end. Between said head and the flange is a coiled spring 103 which presses the rod upwardly and normally holds the pin 91 in the vertical arm of the slot 99, and as the wedge-piece 78 is supported by said latter pin, the spring normally holds the wedge-piece in its uppermost position, as indicated in Figs. 10, 13 and 14. The locking plate, as shown in Fig. 17, has a flange 96a at one side which forms an abutment for a spring 104 interposed between said flange and a flange 105a on a strip 105 which is pivoted on the pin 91. This spring urges the locking plate to the left in Figs. 13 to 17, and hence when the link 90, in which the pin 91 is mounted, is pulled downward until the pin is in line with the horizontal part of the slot 99, the spring moves the locking plate to the left and the pin enters the horizontal part of the slot and is locked against upward movement, as shown in Fig. 15. A rod 106 extends freely through perforations in the flanges 96a and 105a and the spring is coiled around this pin. This rod has a head 106a at one end adapted to engage the flange on the locking plate and move the plate to the right to unlock the pin 91. The opposite end of the rod is pivoted at 107 to the downwardly turned end 108a of a floating lever 108, one end of which is connected by a link 109 to the supporting bracket 40 92. The tripping bar 69 has an extension below the shaft 32 and this extension is pivotally connected at 110 with the floating lever 108.

With this arrangement, when a 50-cent coin is inserted in the machine and the coin controlled lever 13 is rocked, the link 95 rocks the lever 94 and the latter, through the link 93, pulls the lever 90 and the wedge-piece 78 downward until the pin 91 is in line with the horizontal part of the slot 99 in the locking plate, when the spring 104 moves the plate 96 into locking engagement with the pin. As the wedge strip 78 is connected at its lower end to said pin, said strip will be lowered and locked in its lowered position. This movement of the wedge strip adjusts the cams e and f so that only the former can trip the devices which stop the gasoline flow and open the motor switch. As the cam surface 80 on the cam e is back of the cam surface on the cam f, the shaft 32, operated by the metering device and carrying the cams, must be rotated further before the cam e operates the tripping devices, than where these devices are tripped by the cam f, and hence a greater quantity of gasoline will be delivered.

When the bar 69, moved by the cam e, swings over the shaft, its lower end pulls the floating lever 108 outward, as illustrated in Fig. 16, and the head 106a on the pin 106 (Fig. 17) engages the flange 96a on the locking plate and pulls said plate to the right until pin 91 is in line with the vertical part of the slot 99 when the spring 103 pulls said pin and the wedge-piece, which is attached to it, to their upper positions. As the wedge-piece moves upward, the spring 15 on the

shaft 32 presses the cam members e and f back to their normal positions.

Fig. 15 shows the wedge-piece locked in its lower position. The wedge is locked in this position automatically when a 50-cent piece is inserted in the machine and the crank is turned. After the motor has started to pump the gasoline and after the nozzle valve 28 has been opened by the operator, the gasoline flows through the meter 9 and the shaft 32 turns. The cam members move with the shaft and the member e engages the projection 82b on the plate 82 and rocks the bar 69 from its normal position, shown in Fig. 15, to the over-center position shown in Fig. 16, and the rod 68 descends, causing the rod 47 to be released from the latch 55 and the switch b to be opened, whereby the flow of gasoline is stopped and the motor is also stopped, as hereinbefore explained. As the bar 69 swings from the position shown in Fig. 15 to the position shown in Fig. 16, its lower end, which is connected to the floating lever 108, moves the latter horizontally in the direction to bring the head on the rod 106 against the flange 96a on the locking plate and move the latter to release the pin 91, whereupon the spring 103 draws the wedge-piece 78 upwardly to its normal position shown in Fig. 10 and 16 and the spring 75 (Fig. 1) moves the cam members e and f to their normal positions wherein both members lie in the plane of the flange 82b on the plate 82.

The resetting arm 42, which normally stands in the position shown in Figs. 1, 11 and 13, is swung to the left out of the way of the cams, as indicated in Figs. 12 and 14, when the motor is started. But, after the switch which controls the electric motor has been opened by the action of the tripping devices, the spring 46, in which energy derived from the motor is stored, operates the lever 40 and the latter swings the resetting arm 42 back to the position shown in Fig. 13, and in returning to this position it engages the cams and rocks them back to the position shown in said figure.

45 What I claim is:

1. In a liquid dispensing apparatus, an electric motor for pumping the liquid, a switch for starting and stopping said motor, coin-controlled means for closing said switch, a metering device, means actuated thereby for opening said switch after a predetermined quantity of liquid has passed through said device, and means, comprising a spring adapted to be placed under tension by the operation of the motor, for automatically restoring the metering device and the aforesaid switch actuating means to normal positions, after said switch has opened.

2. In a liquid dispensing apparatus, an electric motor for pumping the liquid, a switch for starting and stopping the motor, coin-controlled means for closing the switch, a metering device, a normally closed valve for controlling the flow of liquid through said device, means operated by the motor for opening said valve, means operated by the metering device for causing said valve to close and said switch to open after a predetermined quantity of liquid has passed through said device, and means operating to automatically restore the metering device and the means operated thereby to normal positions, after the switch has opened.

3. In a liquid dispensing apparatus, an electric motor for pumping the liquid, a switch for starting and stopping the motor, coin-controlled means for closing said switch, a meter, tripping

means for opening said switch, means operated by the meter for actuating said tripping means after a given quantity of liquid has passed through the meter, means for adjusting said meter-operated means so as to vary its time of actuation of the tripping means and the quantity of liquid delivered, and means, comprising a spring adapted to be placed under tension by the operation of the motor, for automatically restoring said meter and tripping means to normal positions, after said switch has opened.

4. In a liquid dispensing apparatus, an electric motor for pumping the liquid, a switch for starting and stopping the motor, coin-controlled means for closing the switch, tripping means for opening the switch, a meter, a shaft operated by the meter, cams on the meter shaft, arranged in different angular relations, for actuating said tripping means, means operated by the coin-controlled mechanism for adjusting said cams so that one cam will operate the tripping means if a coin of one size is inserted in the machine and the other cam will operate the tripping means if a coin of larger size is inserted in the machine, and means for restoring said shaft, cams and tripping means to normal positions, after the switch has been opened.

5. In a liquid dispensing apparatus, an electric motor for pumping the liquid, a shaft operated by the motor, a switch for starting and stopping the motor, coin-controlled means for closing the switch, a metering device, a valve for controlling the flow of liquid through said device, a friction clutch on the shaft, a rod connected to and movable by said clutch to open said valve, a spring for moving said rod to close the valve, means operated by said metering device for opening the switch and disconnecting said rod from the clutch after a predetermined quantity of liquid has passed through said device, and means for re-connecting said rod with the clutch after the switch has opened.

6. In a liquid dispensing apparatus, an electric motor for pumping the liquid, a shaft operated by the motor, a switch for starting and stopping the motor, coin-controlled means for closing the switch, a metering device, a valve for controlling the flow of liquid through said device, a friction clutch on the shaft, a rod connected to and movable by said clutch to open said valve, a spring for moving said rod to close the valve, means operated by said metering device for disconnecting said rod from the clutch and for opening said switch after a predetermined quantity of liquid has passed through said device, and means for re-connecting said rod to said clutch, after the switch has opened.

7. In a liquid dispensing apparatus, a motor for pumping the liquid, a switch for starting and stopping the motor, coin-controlled means for closing the switch, a metering device, a shaft operated by said device, a cam member rotatable with the shaft, a bar journaled on the shaft and inclined upwardly therefrom and adapted to be swung into an oppositely inclined position by said cam member, a rod pivotally connected to the upper end of said bar and extending below the shaft, a spring pressing said rod downwardly, means operated by said rod for opening the switch, and means for restoring the meter and the parts operated thereby to their normal positions, after the switch has opened.

8. In a liquid dispensing apparatus, an electric motor for pumping the liquid, a metering device, a switch for starting and stopping the

motor, coin-controlled means for closing the switch, a shaft operated by the motor, a member frictionally driven by said shaft; an outlet valve for the liquid, a rod for opening said valve, said rod having a slot in its lower end, a link connected to said frictionally driven member and having a pin extending into said slot, a latch on

said rod normally engaging said pin, means actuated by the metering device for releasing the latch from the pin and for opening the switch, and means for re-connecting the latch and pin, after the switch has opened. 5
